DOOR CONSTRUCTION

Filed March 13, 1930

UNITED STATES PATENT OFFICE

JOHN A. LOETSCHER, OF DUBUQUE, IOWA, ASSIGNOR TO FARLEY & LOETSCHER MFG. CO., OF DUBUQUE, IOWA, A CORPORATION OF IOWA

DOOR CONSTRUCTION

Application filed March 13, 1930. Serial No. 435,402.

This invention relates to improvements in door construction, and more particularly to a door following generally a construction previously disclosed in an application filed 5 by me on February 17, 1930, bearing Serial No. 428,878, and which may be briefly discussed.

In the manufacture of doors in large quantities, an appreciable saving in the cost per 10 unit is possible by the practice of certain economies in the amount and kind of material used, without an attendant sacrifice of quality or appearance of the product. Considering a standard style of panelled door 15 for instance, the greater bulk of the material is made up of the stiles and rails, that is, the heavy outer frame members which may run from $1\frac{1}{4}$ to 2 inches in thickness and 5 to 6 inches in width, depending on the style 20 of door being made. Clear lumber, free from knots and blemishes, is generally specified for door construction, although relatively expensive, due to the care required in selection and the waste involved. Moreover, the 25 increase in cost of clear lumber is directly proportional to the width and thickness of the material used, and for the obvious reason that the greater the cross-sectional area the greater the degree of care required in its selection. It 30 follows therefore that where a certain width and thickness of material is called for, it is cheaper to use two narrow widths of material joined edge-to-edge than one solid piece provided a joint can be made which will not 35 open with the warping or shrinking of the materials. On this account, it is quite impossible to make a perfectly flush edge-to-edge joint between two pieces of material of the same thickness, but it can be accomplished 40 if one of the pieces is reduced in thickness and set into the edge of the other with a tongue and groove joint.

While this construction is perfectly satisfactory, so far as the door is concerned, it 45 does, however, give rise to one difficulty, namely, the installation of the lock casings which are generally set into a cavity cut in the forward edge of the door frame. Lock casings are made in standard or stock sizes, 50 and these are generally too large to be ap-

plied to a door having the inner portion of the frame of a reduced thickness. Special sizes are obtainable, but this means delay and added expense to the contractor who installs the doors, and therefore it is manifestly better practice to construct the doors to take standard lock casings which can be obtained at any hardware supply store, than to specify special equipment.

The object of the present invention is, therefore, to provide a door construction in which advantage is taken of the more economic construction and yet permit stock size lock casings and fittings to be installed.

A preferred embodiment of my invention 65 is disclosed in the accompanying drawings, in which

Figure 1 is a view in front elevation of a door constructed in accordance with the invention;

Figure 2 is a view in vertical section through the door as taken on line 2—2 of Figure 1;

Figure 3 is a view in cross section through the door taken on line 3—3 of Figure 1;

Figure 4 is an enlarged detail section taken on line 4—4 of Figure 1; and

Figure 5 is an enlarged detail section taken on line 5—5 of Figure 1.

The door illustrated is made up generally 80 of an outer frame consisting of vertical stiles 1, 1, a top rail 2 and a bottom rail 3 of, say, $1\frac{3}{8}$ or $1\frac{5}{16}$ inches in thickness surrounding three thin central panels 4, 5, and 6 of, say, $\frac{3}{8}$ or $\frac{5}{16}$ inches in thickness and separated by 85 two parallel cross rails 7, 7 of the same thickness as the outer stiles and rails. The cross rails are located approximately midway of the height of the door, and fairly close together, so that the intermediate panel 5 is 90 quite narrow while the upper and lower panels 4 and 6 are considerably wider, the upper panel being the larger of the two. While the height of the panels may vary, the only requirement is that the lock 8 which is 95 usually placed at a prescribed height above the floor along the front edge of the door shall be located between the two cross rails 7, 7.

The stiles 1, 1 are, say, 3 or $3\frac{1}{4}$ inches in 100 width, the top rail 2 about the same width,

while the bottom rail 2 is usually considerably wider, say, 8 inches, these members being joined at their ends by dowelled or mortise and tenon joints.

In making up these outer stiles and rails, the material used is of standard thickness, but considerably less in width than is the requirement for this particular grade of door. For example, if the specifications call for a 10 stile 5 inches in width, the width of the stile member 1 may be only 3 inches, the full width of the stile being obtained by adding a narrow stile 2 inches in width along the inner edge of the outer stile 1, which extends between the same and the thin central panel. Thus in the present construction the outer stiles 1, 1 and rails 2, 3, and 7 are made of pieces of lumber of full thickness but of reduced width, to form a separate outer frame, 20 which is increased to the standard width by narrower supplementary inner stile and rail members forming inner frames surrounding the larger upper and lower panels 4 and 6. Each inner frame consists of a stile 9 and a rail 10 joined together at their ends by a dowelled or mortise and tenon joint and along their outer edges to the inner edges of the outer frame members and the cross rails 7, 7 in a manner presently described. The 25 treatment of the intermediate panel 5 is slightly different from that of the upper and lower panels 4 and 6 in that there is no inner frame between it and the heavier frame members surrounding it, although short vertical stile sections 11, 11 are provided at each end, which correspond to the stiles 9, 9 along the vertical edges of the upper and lower panels.

In the case of the inner stiles and rails 9, 9 and 10, 10 forming the inner frames for the upper and lower panels, it will be noted that they are thinner than the outer stiles and rails—the difference being, say, one-quarter of an inch. Each inner stile and rail has a tongue and groove connection with its corresponding outer stile and rail, the inner edges of the outer stiles and rails being rabbed to form a deep square groove 12, with right-angled shoulders or offsets 12a on either side, while the outer edges of the inner stiles and rails are formed with tongues 13 to fit within the grooves, the joints being made secure by applying glue to the contacting surfaces. The inner edges of these stiles and rails 9 and 10 are preferably beveled and rabbed to receive the edges of the thin panels 4 and 6, this being also true of the inner edges of the cross rails 7, 7, which have direct connection with the top and bottom edges of the intermediate panel 5, without a narrow rail between.

The short inner stiles 11, 11 at either side of the intermediate panel 5, are similar in all respects to the stiles 9, 9 except that they have the same thickness as the outer stiles 1, 1 so that the portions of the vertical stiles between

the cross rails 7, 7 are of uniform and full thickness throughout their entire width.

Manifestly it is in one of these portions of the stiles that the lock is to be installed, and it follows that the increased thickness of the inner stiles 11, 11 makes it possible to cut the square cavity for the lock casing 8a which is assumed to be of a standard size for the door, and which otherwise could not be accomplished without first building up the inner stile to the same thickness as the outer stile, and this manifestly would mean additional labor and a patchy undertaking at best. Thus as shown in Figure 1, the lock casing would be sunk well into the inner stile section 11, but with the same thickness of stile throughout the installation can be made as readily as though the stile were solid throughout its full width. Likewise in applying the escutcheon plates 8b of the lock on the outer faces of the door, there is an ample width of flush surface for them to face against without having their inner edges projecting over a shoulder as would otherwise be the case.

Such a door construction therefore makes it possible to take advantage of the economy in cost of manufacture by utilizing materials of different width and thickness for the stiles and rails and at the same time solves the problem of using standard locks without necessitating any subsequent alterations or detracting from the general appearance of the door.

Having set forth a preferred embodiment of my invention,

I claim:

1. A door construction comprising vertical stiles, top, bottom, and intermediate cross-rails consisting of relatively narrow lengths of material joined together edge-to-edge, and thin panels fitted into the spaces surrounded by said stiles and rails, the material forming the inner portions of said stiles and rails on opposite sides of the cross-rails being of reduced thickness, and the portions forming the stiles of the panel intermediate said cross-rails being of equal thickness.

2. A door construction comprising vertical stiles, top and bottom rails joined together at their ends to form an outer frame and consisting of two lengths of material joined together edge-to-edge, a pair of cross-rails spaced apart adjacent the central portions of the door and dividing the frame into three rectangular spaces, and thin panels fitted into said spaces, the innermost lengths of material comprising said stiles and rails being of reduced thickness and forming separate frames surrounding the panels above and below said cross-rails, and the lengths forming the stiles adjacent the intermediate panel being of the same thickness as the outer frame.

3. A door construction comprising an outer frame of stiles, top and bottom rails and a

pair of parallel spaced cross-rails intermediate said top and bottom rails, an inner frame of stiles and rails of reduced thickness fitted into the outer frame above and below said cross-rails, inner stiles joined edge-to-edge with the stiles of said outer frame and extending between said cross-rails and panels fitted into said inner frames and in the space included by said cross-rails and inner stiles, the latter having the same thickness as said outer stiles.

4. A door construction comprising relatively narrow stiles and rails forming an outer frame of predetermined thickness, a pair of cross-rails of the same thickness spaced apart intermediate the top and bottom rails, inner stiles and rails of decreased thickness forming separate frames fitted into the spaces in said outer frame surrounding the spaces enclosed on either side of said cross-rails, and having tongue and groove connection along their edges therewith, thin panels surrounded by said inner frames, and a panel in the space between said cross-rails, the ends of said panel being flanked by narrow inner stiles of the same thickness as the adjacent portion of the outer stiles.

5. A door construction comprising relatively narrow stiles and rails forming an outer frame of predetermined thickness, a pair of cross-rails of the same thickness spaced apart intermediate the top and bottom rails, inner stiles and rails of decreased thickness forming relatively narrow frames surrounding the spaces enclosed by the stiles and rails of the outer frame and said cross-rails, thin panels surrounded by said inner frames, inner stiles of the same thickness as the stiles of said outer frame extending vertically at each end of the space between said cross-rails, and a panel fitted into the adjacent edges of said cross-rails and said last mentioned inner stiles.

Signed at Dubuque, Iowa, this 7th day of March, 1930.

JOHN A. LOETSCHER.
